ATTORNEY

UNITED STATES PATENT OFFICE.

CHAUNCEY D. FRENCH, OF SEATTLE, WASHINGTON.

SIGNAL DEVICE.

1,285,669.

Specification of Letters Patent. Patented Nov. 26, 1918.

Application filed May 26, 1917. Serial No. 171,269.

To all whom it may concern:

Be it known that I, CHAUNCEY D. FRENCH, a citizen of the United States, residing at Seattle, in the county of King and State of Washington, have invented certain new and useful Improvements in Signal Devices, of which the following is a specification.

This invention relates to signal devices, and more particularly to a hand traffic signal adapted especially for use at intersecting streets, railroad grade crossings, and the like where it is necessary to warn approaching vehicles to avoid accidents.

One of the objects of the invention is to provide an illuminated signal adapted to be held in the hand of the traffic guard or watchman and manipulated in the manner similar to the ordinary flash light, for the purpose of displaying an illuminated warning signal during the night hours.

The invention also aims at the provision of a novel signal adapted to be easily manipulated in one hand, and provided with light intensifying elements in the form of reflectors or the like.

A further object of this invention is the provision of a signal device which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a front elevation.

Fig. 2 is an edge elevation.

Fig. 3 is a section on the line 3—3 of Fig. 2.

Fig. 4 is a section on the line 4—4 of Fig. 3.

Referring to the drawing, wherein is illustrated the preferred form of my invention, and in which like numerals of reference indicate corresponding parts throughout the several views, the cylindrical casing 1 is constructed of a size suitable to serve as a handle that may be conveniently held by the traffic guard or watchman at intersecting streets or railroad grade crossings, so that one hand will be free to hold a signal whistle or the like, while the other manipulates the illuminated signal. The interior of the handle

or casing receives a flash light 2 of the well known type, the same consisting of the cylindrical battery casing having a "bull's-eye" 3, mounted at one end and disposed near the upper end of the casing 1. The lower end of the casing is open and carries a hinged closure 4, the edge of which provides a tongue adapted to be received in a notch 5, provided on the inner surface of the finger 6. This latch is constructed from an extended portion of the casing, cut from the lower end thereof as clearly shown by Figs. 2 and 3 of the drawing, and it will be obvious that this latch will have sufficient resiliency to permit it to be pulled outwardly for causing the closure 4 to open, whereby the flash light may be removed from the casing or replaced therein. At the upper end of the casing, at diametrically opposite points, the same is provided with indentations 7 adapted to engage the sides of the flash light to rigidly hold it in position and prevent rattling or movement of the flash light in the casing.

Attached to the upper end of the casing is the signal drum 8 which consists of an outer shell 9 constructed of thin metal or the like, and attached to the upper end of the casing 1 in any preferred manner. An opening in the shell communicates with the interior of the casing, and the "bull's-eye" 3 is disposed in the opening, so that the interior of the drum will be illuminated when the light is energized. In this connection, it is pointed out that the light has a push button 10 protruding through an opening 11 in the casing 1, whereby the operator may conveniently reach the button by one of his fingers to operate the light. An interior chamber 11 is mounted in the shell 9, and the rear wall 12 thereof is preferably constructed from a suitable polish metal, or the like for the purpose of acting as a reflector when the light is in operation. The front of this chamber is provided with a glass panel 13 upon which the word "Stop" is printed, and it will be apparent that when the interior of the chamber is illuminated by the light, this word will be clearly visible and will stand prominently upon the illuminated glass panel. The interior of the chamber is also provided with an angularly disposed reflecting plate 14, and the rays of light from the "bull's-eye" 3 will be deflected from the angularly disposed reflecting plate 14 to the reflector 12, so that a maximum illumination will be

obtained from a comparatively small light in the "bull's-eye".

A ring 15 is fastened to the top of the shell 8, whereby the device may be hung from a 5 convenient hook or the like when not in use. At one side of the casing 1, I have provided a screw-eye 16 which will serve as a convenient hook for a signal whistle or other signal generally used for sounding audible 10 signals in congested traffic. It will be apparent, that if desired, the signal may be provided with colored glass according to the duty of the signal and the various places in which it may be used.

15 A particular advantage of the device lies in its comparative simplicity and small size and, inasmuch as certain congested districts in large cities cannot conveniently sacrifice the space required for the ordinary signal 20 stand and semaphores, the present device may be conveniently used by the traffic guard when a heavy rain is falling or a thick fog prevents the use of the ordinary gesticulations easily visible in fair weather 25 and daylight. Furthermore, the device may be held in one hand, while the traffic guard manipulates his signal with the other, and the light may be extinguished or energized by a simple pressure on the push button.

30 From the foregoing it will be observed that a very simple and durable signal device has been provided, the details of which embody the preferred form. I desire it to be understood, however, that slight changes 35 in the minor details of construction may be made without departing from the spirit of the invention or the scope of the claims hereunto appended.

I claim:

40 1. A signal device of the character described comprising a casing forming a handle and having a flash-light mounted therein, and a drum mounted upon the casing and provided with a glass panel having signal 45 characters arranged thereon, and disposed to receive the light rays from the said flash-light.

2. A signal device of the character described comprising a casing of a size to 50 form a convenient handle, a flash-light arranged within the handle and provided with a push button exposed for access from the

exterior of the handle, and visible signaling means mounted upon the casing and adapted to be illuminated by the said flash light. 55

3. A signal device of the character described comprising a casing having an opening provided therein, a flash light mounted in the casing and provided with a push button protruding through the opening, the 60 flash-light having a "bull's-eye" disposed at the end of the casing, a drum mounted upon the casing and provided with an exteriorly disposed transparent panel having display characters arranged thereon, and reflecting 65 means for receiving the light rays from the said "bull's-eye" to transmit the same through the said transparent panel.

4. A traffic signal of the character described comprising a signal drum having a 70 relatively small opening in its cylindrical wall, a transparent panel mounted in one end of the drum and a reflecting element in the opposite end thereof, and means for illuminating the interior of the drum through 75 the said opening, and for providing a handle therefor.

5. A traffic signal of the character described comprising a signal drum having a 80 relatively small opening in its cylindrical wall, a transparent panel mounted in one end of the drum and a reflecting element in the opposite end thereof, an angularly disposed reflecting plate mounted within the drum and coöperating with the said reflecting element, an illuminating means connected with the drum and adapted to throw light rays through the said opening on the 85 said angularly disposed reflector, to illuminate the transparent panel. 90

6. A traffic signal device comprising a drum having a transparent panel mounted therein, the latter bearing signal characters, a casing attached to the drum and provided with a lighting element, one end of the casing being open and in communication with the drum, and means for opening and closing the opposite end of the casing. 95

In testimony whereof I affix my signature in presence of two witnesses.

CHAUNCEY D. FRENCH.
